(57) CLAIM

The ornamental design for portable UV sterilizer, as shown.

DESCRIPTION

FIG. 1 is a perspective view taken from above and the front and right sides of the portable UV sterilizer of the present invention;

FIG. 2 is a front elevational view of the portable UV sterilizer of the present invention;

FIG. 3 is a rear elevational view of the portable UV sterilizer of the present invention;

FIG. 4 is a left side elevational view of the portable UV sterilizer of the present invention;

FIG. 5 is a right side elevational view of the portable UV sterilizer of the present invention;

FIG. 6 is a top plan view of the portable UV sterilizer of the present invention; and,

FIG. 7 is a bottom plan view of the portable UV sterilizer of the present invention.
